UNITED STATES PATENT OFFICE.

AUGUST KELLER, OF BERLIN-LICHTERFELDE, GERMANY.

PULVERIZER MILL.

Application filed January 25, 1924. Serial No. 688,435.

To all whom it may concern:

Be it known that I, AUGUST KELLER, a citizen of Germany, residing at Berlin-Lichterfelde, Germany, have invented certain new and useful Improvements in Pulverizer Mills, of which the following is a specification.

My invention refers to pulverizer mills and more particularly to a mill of the type in which a number of balls are kept running in a circular race-way by means of pushers kept in constant circular motion, the particular object being to improve the efficiency and durability of such mills.

It is a further object of my invention to avoid as far as possible all friction between the balls and the pushers driving them and, at the same time, to reduce the wear of the balls and pushers with a view to lengthening the life of these parts.

It is a further object of my invention to provide means for regulating with great nicety the supply of fresh material to the balls.

It is another object of my invention to improve the discharge of the ground material as well as of the dust from the mill, the first being effected by mechanical means, the last mainly pneumatically.

It is still another object of my invention to provide means for preventing the driving gear of the mill from breaking in the case where the mill should for some unforeseen reason come to a dead stop.

With these and other objects in view, my invention consists in the improvements more fully described hereinafter and disclosed in the drawings annexed to this specification and forming part thereof, the pulverizer mill shown in the drawing by way of example being fitted with all these improvements.

In the drawings—

Fig. 1 is a vertical section of the mill,

Fig. 2 is a cross-section on the line II—II in Fig 1.

Fig. 3 is an axial section, drawn to a larger scale, of one of the pushers.

Fig. 4 is a vertical cross-section of the cover and charging device, while

Fig. 5 is a plan view thereof.

Referring to the drawings, 1 is the substantially cylindrical base of the mill, 2 is a conical cover plate carrying a bearing for the vertical shaft, 3 is a cylindrical standard placed on top of the cover plate and

base. 4 is a casing and 5 is the annular chamber from which the material is evacuated. 6 and 7 are concentric cylindrical screens and 8 is the outer cylindrical shell 60 surrounding the upper part of the mill. 9 is the upper cover plate, 10 is an annular flange formed thereon and having discharge slots 12 formed therein. 13 is an annular casing of triangular section surrounding the 65 cover, 14 is the exhaust connected with a suction fan. 15 is the longitudinal driving shaft located in dust-proof ball bearings 16 and 17, respectively and bearing a cog wheel 18 meshing with the large cog-wheel 19 on 70 the lower part 20 of the vertical operating shaft composed of two separate parts for the purpose to be disclosed later on. Part 20 of this shaft is located in a ball bearing 21 mounted on the base 1 and another ball 75 bearing 22 carried by the plate 2. A disc 23 fixed to the upper part 24 of the vertical shaft is rotatably supported by balls 25 running in a race-way 26 fixed to the top portion 27 of the standard 3. On this top 80 portion rests the grinding ring or race-way 28 holding the grinding balls 29. 30 is the yoke fixed to shaft 24 above ring 28 and carrying the downwards extending pushers 31 and inclined lifting blades 32, an aperture 33 allowing fresh material to drop into the ring 28. 34 is a cylindrical jacket mounted on the yoke 30 and 35 is a funnel suspended from the cover plate 9 and extending concentrically with the jacket with 85 its lower end in close proximity to the yoke 30. The upper end of shaft 24 extends upwards through the aperture 36 of the cover plate 9 and is here supported by another ball bearing 37. A pinion 38 keyed onto the 90 projecting end of the shaft meshes with an intermediate gear wheel 39 turning about a journal 40 projecting from the cover plate and carrying a smaller wheel 41 meshing with the toothed rim 42 of the feeding plate 100 43 rotatably mounted on plate 9. A larger wheel 44 driven by wheel 39 is keyed onto an intermediate shaft 45 located in bearings 46, 47 and extending alongside of the outer shell 8. A gear wheel 48 keyed to the lower end of intermediate shaft 45 serves for driving the expeller ring 49 carrying scraper blades 50. Ring 49 rests on rollers 51 turning about journals lodged in the outer wall 105 of the chamber 5.

One of the pushers 31 is shown in Figure 3 in axial section. In a conical seat 52 of

the arm suspended from the yoke 30 a journal 53 is secured by means of a nut 54 and washer 55. 56 is a cap surrounding the projecting portion of journal 53. 57, 58 are 5 roller bearings inserted between the parts and taking up radial friction, while a ball bearing constituted by a race-way 59 fixed to the cap 56 and another race-way 60 fixed to the journal with balls inserted between 10 them takes up the axial thrust. The cap is prevented from gliding off the journal by a ring 61. On the circumference of the cap there is mounted a conical sleeve 62 of hardened material highly resistive against 15 abrasion. In cooperating with a grinding ball 29, the cap 56 and conical sleeve 62 act like a roller, revolving in contact with the ball and thereby preventing both the ball and pusher from being worn out, as is the 20 case with the balls and pushers in the pulverizing mills hitherto known, in which the pushers exert a braking effect on the balls, thereby causing not only a great and useless waste of energy, but also necessitating 25 frequent exchange of both balls and pushers.

The pusher rolls being situated on their journals with the interposition of ball and roller bearings, revolve almost without friction and therefore necessitate the least possible expenditure of motive power. In cases where the material to be ground enters the mill in heated condition, I provide for an effective cooling of the rollers by means 30 of water circulating within the cap.

35 The feeding plate shown more particularly in Figs. 4 and 5 substantially consists of the rotary plate 43 designed to receive the fresh material to be fed into the mill and a scraper 63 disposed in a plane extending 40 eccentrically across the upper surface of the plate 43 and being adjustable in longitudinal direction, the rear end of the scraper 63 projecting from a guide 64 being attached to a sleeve 65 adjustably mounted on a spindle 66. 45 governed by means of a hand wheel 66. With the plate 43 rotating in the direction of the arrow (Fig. 5) the material placed thereon, on meeting the scraper 63, will be thrown off the plate 43, to drop into a funnel 50 67 surmounting the aperture 68 which leads into the funnel 35 and to the aperture 33 in the yoke 30. According to the length of that portion of the scraper 63 which extends across plate 43, more or less material will be 55 held up by the scraper and be caused to drop off. In this manner a very exact regulation of the quantity fed into the mill can be obtained. By casting the plate 43 and the toothed rim 42 in one piece, the constructional height of the feeding plate is kept 60 very low.

65 As mentioned above, the vertical main shaft is composed of two parts 20 and 24. A coupling sleeve 69 is mounted on the upper end of part 20 and firmly connected there-

with by a key 70. A pin 71 traversing the upper end of sleeve 69 and the lower end of shaft 24 forms the connection between these two parts. However, the shearing strength of this pin is so chosen that, if the upper 70 part of the mill including the pushers and balls should for some reason come to a dead stop, the pin will break or be shorn off and, in thus disengaging the two parts of the vertical shaft, prevent the cog wheels driving the shaft from breaking or getting damaged.

The above described mill operates as follows:—

The material deposited on the feeding 80 plate 43 is caused by the scraper 63 to drop through the funnel 67 and aperture 68 into the funnel 35 and through aperture 33 into the grinding chamber proper.

The material, after having been pulverized, will be lifted from the zone of operation of the grinding walls by the upwardly moving currents of air due to the action of the fans 32. Carried by these air currents, 90 the heavier and larger particles will be separated by gravity and will fall back into the pulverizing zone and be reground between the balls and the grinding rings, while the lighter material passing with the air currents through the screens 6 and 7 will settle 95 in the annular chamber 5, being expelled therefrom by the scrapers 50 which, owing to a suitable gearing interposed between ring 49 and pinion 38 on the main shaft, revolves only very slowly, thereby preventing 100 the raising of great masses of dust. The comparatively small quantities of floating particles are removed by suction, a fan 72 being arranged to act on the exhaust 14, the annular chamber 13 and slots 12 in the 105 flange 10 of cover plate 9.

In contradistinction to pulverizing mills hitherto known, in which rapidly rotating fans operating in an annular chamber similar to chamber 5 were employed for expelling the ground material, the slowly revolving scraper ring offers the advantage of preventing generation of dust escaping through the exhaust. On the other hand, the large 110 sectional area of the settling chamber confined between the shell 8 and the screens 6 and 7 and the provision of narrow exhaust slots 12 evenly distributed all over the circumference of the cover flange 10 allow the air to be drawn from the large annular space 115 in a uniform manner and with a very low velocity, the air thus escaping freely through all the meshes of the screens and thereby preventing their being clogged. Owing to this slow velocity of the air, the finely ground particles have time to settle and to be caught by the scrapers 50.

All the shafts 15, 20 and 24 being located in ball bearings exclusively, all these bearings being enclosed in dust tight shells, 120

the losses due to friction are minimized and a great saving in motive power is obtained. The advantages offered by providing the pushers with revoluble heads have been fully explained before.

I wish it to be understood that I do not desire to be limited to the exact details of construction shown and described, for obvious modifications will occur to a person skilled in the art.

I claim:

1. In a pulverizing mill, a grinding ring, a grinding ball in said ring, and a pusher member coacting tangentially with said ball and having a constantly shifting and rolling contact therewith.
2. The combination, with a pulverizer mill, of a grinding ring, a grinding ball in said ring, a shaft, a pusher arm connected with said shaft for circular motion in said ring and a revoluble member connected with said pusher arm and adapted to cooperate with said ball, said revoluble member having a conical contact face substantially tangential to the surface of the ball whereby to provide for a minimum frictional contact with the ball and permit free movement of the latter relative to the member.
3. In a pulverizing mill, a grinding ring, a grinding ball in said ring, a pusher arm, means for actuating said arm, a roller member mounted on said arm coacting tangentially with said ball and having a constantly shifting and rolling contact therewith, and friction reducing means inserted between said roller and said pusher arm.
4. In a pulverizing mill, the combination of a shell, a grinding ring therein, a

grinding ball adapted to travel about said ring, a revolving unit within said shell composed of a receptacle adapted to receive the material to be ground and having an opening in the base thereof immediately over the ring and ball to distribute the material thereto, a pusher arm depending from said receptacle having a roller member coacting with the ball, said receptacle having an exterior blade member adapted to impart a lifting action to the pulverized material to propel it to the collecting chamber, and a collecting chamber extending about said shell to receive the pulverized material.

5. The combination, with a pulverizer mill, of a vertical main shaft, extending centrally through said mill, a vertical shaft extending alongside of said mill and gearing with said main shaft, an annular chamber, surrounding said main shaft, a ring and scrapers removably mounted in said chamber, and means on said second shaft for revolving said ring and scrapers at low velocity.

6. The combination, with a pulverizer mill, of grinding means arranged in the centre of said mill, a screen surrounding the space above said grinding means, means within said space for generating an outwardly directed air current, a shell surrounding said screen in spaced relation thereto, so as to form an outer annular space of large sectional area, a slotted cover at the upper end of said space and suction means adapted to act on said slots.

In testimony whereof I affix my signature.

AUGUST KELLER.
